CLAIM

The ornamental design for a surgical face shield for a surgical hood, as shown and described.

DESCRIPTION

FIG. 1 is a top, front right-side perspective view of a surgical face shield for a surgical hood showing our new design; FIG. 2 is a partial enlarged view of FIG. 1; FIG. 3 is a partial enlarged view of FIG. 4; FIG. 4 is a rear, bottom right-side perspective view thereof; FIG. 5 is a front view thereof; FIG. 6 is a rear view thereof; FIG. 7 is a partial enlarged view of FIG. 5; FIG. 8 is a partial enlarged right-side view of FIG. 10; FIG. 9 is a partial cross-sectional view taken along the axis of FIG. 7; FIG. 10 is a right-side view thereof; FIG. 11 is a left-side view thereof; FIG. 12 is a top view thereof; FIG. 13 is a bottom view thereof; and, FIG. 14 is a partial enlarged bottom view of FIG. 13. The broken lines included throughout the figures are merely included to identify a region that is enlarged in a subsequent figure and forms no part of the claimed design.
